(57) **CLAIM**

The ornamental design for an oscillating irrigator, as shown and described.

DESCRIPTION

FIG. 1 is a front perspective view of the present design of an oscillating irrigator;

FIG. 2 is a rear perspective view of the present design of an oscillating irrigator;

FIG. 3 is a top view of the present design of an oscillating irrigator;

FIG. 4 is a bottom view of the present design of an oscillating irrigator;

FIG. 5 is a left side elevation view of the present design of an oscillating irrigator;

FIG. 6 is a right side elevation view of the present design of an oscillating irrigator;

FIG. 7 is a front elevation plan view of the present design of an oscillating irrigator; and,

FIG. 8 is a rear elevation plan view of the present design of an oscillating irrigator.
